UNITED STATES PATENT OFFICE.

HUGO BORCHARDT, OF CHARLOTTENBURG, GERMANY.

BREECH MECHANISM FOR AUTOMATIC FIREARMS.

1,184,065.

Specification of Letters Patent.

Patented May 23, 1916.

Application filed February 2, 1914. Serial No. 816,046.

To all whom it may concern:

Be it known that I, HUGO BORCHARDT, a citizen of the United States of America, residing at 31 Kantstrasse, Charlottenburg, 5 near Berlin, in the Empire of Germany, have invented certain new and useful Improvements in Breech Mechanism for Automatic Firearms, of which the following is a specification.

10 The object of the invention is to provide a breech mechanism for automatic firearms allowing of its automatic operation even when blank cartridges are being used. In this connection it has already been proposed to increase the gas pressure by using 15 a choked barrel or choked blank cartridge shells.

According to the invention the problem is solved by decreasing the work to be effected by the gas pressure when shooting blank cartridges by displacing or altering the breeches members. In an automatic firearm having a toggle breech this can be effected, for instance, by inserting between 20 the toggle joint and the breech casing a lifting block which bears upon the wall of the casing so as to lift or partly break the joint.

A constructional form embodying the invention is represented in the accompanying 25 drawing, in which:

Figure 1 is a longitudinal view, partly in section, Fig. 2 is a perspective view of the lifting block, Figs. 3 and 4 are two vertical transverse sections taken through the 30 middle hinge of the toggle joint, showing respectively the lifting block in place and the same omitted.

The recessed middle hinge *c* of the two arms *a* *b* of the toggle joint bears directly 40 on the wall of the breech casing *g*, when the firearm is being used with ball cartridges. When blank cartridges are to be employed a lifting block *d* is inserted in the toggle joint so as to bear on the wall 45 of the breech casing *g*.

The lifting block *d* partly breaks the toggle joint by raising the middle hinge slightly above the position which it assumes under normal conditions. The elevation 50 of the toggle joint is clearly shown in Fig. 3 in which the lifting block *d* is inserted in position, as contrasted with Fig. 4 in which it is omitted.

The toggle joint being partly broken by 55 inserting the lifting block, the work to be effected by the gas pressure is decreased

to such an extent that the automatic operation of the firearm can take place in the same manner as when ball cartridges are used.

The lifting block *d* (Fig. 2) is provided or formed with an upper resilient spur *e* bearing on the joint *c*, and with a central projection *f* engaging a corresponding recess *f'* formed in the said joint. This permits of its easy detachment and insures a secure seat for the lifting block.

What I claim and desire to secure by Letters Patent of the United States is:

1. Breech mechanism for automatic firearms comprising a breech block, a breech casing, a toggle joint connecting said breech block with said breech casing, and detachable means disposed between said breech casing and said toggle joint and adapted to 70 lift the middle hinge of said toggle joint.

2. Breech mechanism for automatic firearms comprising a breech block, a breech casing, a toggle joint connecting said breech block with said breech casing, and detachable means bearing upon the wall of said breech casing and adapted to partly break 80 said toggle joint.

3. Breech mechanism for automatic firearms comprising a breech block, a breech casing, a toggle joint connecting said breech block with said breech casing, and detachable means inserted in the toggle joint and bearing upon the wall of said breech casing and adapted to partly break 85 said toggle joint.

4. Breech mechanism for automatic firearms comprising a breech block, a breech casing, a toggle joint connecting said breech block with said breech casing, and detachable means disposed between said breech casing and the middle hinge of said toggle joint and adapted to lift 90 said middle hinge.

5. Breech mechanism for automatic firearms comprising a breech block, a breech casing, a toggle joint connecting said breech block with said breech casing, and a detachable lifting block disposed between said breech casing and said toggle joint for increasing the angle of opening of said toggle 100 joint.

6. Breech mechanism for automatic firearms comprising a breech block, a breech casing, a toggle joint connecting said breech block with said breech casing, and a detachable lifting block disposed between said casing and said toggle joint and yieldingly 110

engaging said toggle joint for increasing the angle of opening of said toggle joint.

7. Breech mechanism for automatic fire-arms comprising a breech block, a breech casing, a toggle joint connecting said breech block with said breech casing, a detachable lifting block disposed between the central hinge of said toggle joint and said breech casing, an upper resilient spur on said lifting block bearing on said joint, a recess in

said joint, and a projection on said lifting block engaging said recess, substantially for the purposes specified.

In testimony whereof I affix my signature in presence of two witnesses.

HUGO BORCHARDT.
